FREDERICK R. SEIDENSTICKER, OF WEST MERIDEN, CONNECTICUT,
ASSIGNOR TO BRADLEY & HUBBARD, OF SAME PLACE.

Design No. 4,770, dated April 4, 1871.

DESIGN FOR LAMP-BRACKETS.

The Schedule referred to in these Letters Patent and making part of the same.

To all whom it may concern:

Be it known that I, FREDERICK R. SEIDENSTICKER, of West Meriden, in the county of New Haven and State of Connecticut, have invented a new Design for Lamp Bracket; and I do hereby declare the following, when taken in connection with the accompanying drawings and the letters of reference marked thereon, to be a full, clear, and exact description of the same, and which said drawings constitute part of this specification and represent a side view.

This invention relates to a design for a bracket for the support of the burner, here represented as for supporting a kerosene lamp, and consists in the form of the bracket from the place for attachment to the wall forward to the burner or support, as more fully hereafter described.

From the attachment *a* a straight arm, *d*, projects a short distance, when it suddenly drops into a curved form, *c*, with a sustaining brace, *b*, below, extending from the part *c* to the part *d*, with an ornament, *f*, above, to which, if required, the reflector-spindle may be attached, the spindle *h* being no part of the design.

The part *c* terminates at the burner or holder, as the case may be, and this design applies as well to gas brackets as to lamps.

I claim as my invention—

The design for lamp-bracket, as herein described and shown in the accompanying photographic illustrations.

FREDERICK R. SEIDENSTICKER.
